TREATING MACHINE FOR FLOOR, WALL AND CEILING SURFACES OR THE LIKE

Harold T. Sawyer, Los Angeles, Calif., assignor of seventeen and one-half percent to Vernon D. Beehler, Los Angeles, Calif.

Filed Jan. 25, 1966, Ser. No. 766

Term of patent 14 years

(Cl. D9—2)

FIGURE 1 is a side perspective view of a treating machine for floor, wall and ceiling surfaces or the like showing my new design;

FIGURE 2 is a front elevational view thereof; and
FIGURE 3 is a side elevational view thereof.

The side not shown has substantially the same appearance as the side shown.

The dominant features of my design reside in the portions shown in full lines.

I claim:

The ornamental design for a treating machine for floor, wall and ceiling surfaces or the like, as shown and described.
